Attorney, Agent, or Firm—Richard B. O'Planick

[57]

CLAIM

The ornamental design for a food container lid, as shown and described.

DESCRIPTION

FIG. 1 is a front perspective view of a food container lid showing my new design;
 FIG. 2 is a top plan view thereof;
 FIG. 3 is a front elevational view thereof; the left side elevational view being a mirror image;
 FIG. 4 is a right side elevational view thereof; the rear elevational view being a mirror image; and,
 FIG. 5 is a bottom plan view thereof.
